SUPPORT FOR TUBE FRAMES IN
AXMINSTER LOOMS

Edward J. Dacey, Philadelphia, Pa., assignor to
Crompton & Knowles Loom Works, Worcester,
Mass., a corporation of Massachusetts

Application November 1, 1933, Serial No. 696,261

3 Claims. (Cl. 139—9)

This invention relates to improvements in tube frame supports for Axminster looms and it is the general object of the invention to provide means to support the tube frame during the wiping-in 5 operation.

In my co-pending application Serial No. 623,583 I have shown a brace for a tube frame used in the weaving of a fabric wherein the pattern appears on the back. That application shows a plurality of guide plates to define guide aisles with the reed dents, and the yarn tubes of the tube frame are moved between the guide plates with a resultant frictional tendency to bow the tube frame rearwardly. The brace in that application moves against the tube frame while the latter is in an inclined position, the force being directed substantially horizontal. The clutches which hold the tube frame during the wiping-in operation are in an inclined position at the time the tube frame is pushed forwardly by the brace, and there is a tendency for the brace to move the tube frame out of the clutches.

It is an important object of my present invention to provide means for keeping the tube frame seated in the clutch while the brace is in operation. In certain types of Axminster looms the tube frame is moved down by a spring acting in addition to gravity and I find that a force sufficient to brace the tube frame will not lift the transerrer arms, and the latter effectively hold the clutches against upward movement.

It is a further object of my present invention to provide an actuating roll or the like to assist in the proper motion of the brace or support for the tube frame. During the wiping-in operation the tube frame is raised from a low inclined position to one that is higher and substantially erect and the brace should remain in contact with the tube frame as the latter rises. As shown herein I provide a fixed guide, as a roll, to engage part of the brace actuator connections to require the brace to move up with the tube frame.

While I have shown the invention as usable more particularly with the type of spacing plates set forth in co-pending application Serial No. 575,190, yet I do not wish to be limited to plates of this type, inasmuch as any form of guides for tuft yarns in addition to the binder and stuffer warps will increase the frictional resistance offered to the yarn tubes and therefore tend to bow the tube frame rearwardly, and the structure set forth hereinafter is usable to prevent the bowing, whatever the cause.

With these and other objects in view which will appear as the description proceeds, my invention

resides in the combination and arrangement of parts hereinafter described and set forth in the claims.

In the accompanying drawings, wherein a convenient embodiment of my invention is set forth,

Fig. 1 is a view in end elevation, parts being in section of the upper part of an Axminster loom having my invention applied thereto,

Fig. 2 is an enlarged detailed section on line 2—2 of Fig. 1 showing the tube frame, bracket and clutch, together with the connections for temporarily holding these parts together,

Figs. 3, 4 and 5 are diagrammatic views showing successive positions through which the tube frame and the brace pass during the wiping-in 15 operation,

Figs. 6 and 7 are diagrammatic views similar to a portion of Fig. 1 showing the tube frame brace and operating mechanism therefor in different positions,

Fig. 8 is a diagrammatic view showing the relation between the yarn tubes and the guide plates,

Fig. 9 is an end view of the structure shown in Fig. 6, and

Fig. 10 is a plan view of the structure illustrated in Fig. 8.

Referring to the drawings, the loom frame 20 has a bottom shaft 21 having a cam plate 22 secured thereto. A pullover shaft 23 has a sprocket 24 by means of which the transporting chain 25 is 30 given progressive steps to present the tube frames one at a time to delivery position.

Each tube frame 26, an end of one of which is shown in Fig. 2, comprises a bar 27 which may be tubular and have secured thereto an upstanding chain engaging arm 28 and a spool supporting arm 29. The spool 30 carries the usual yarn supply, the separate yarns being moved down through the yarn tubes 31. In the present instance the attaching hook 32 may be rigid and 40 have an upper end to overhang the chain 25.

Normally the hook is held yieldingly in supporting position by a spring 33 surrounding a tongue 34 which moves with the hook, and at the time of transfer the clutches, one of which 45 is shown at 35 in Fig. 2, move inwardly so that an unlatching lug 36 passes through a slot 37 in the arm 28 and into engagement with the hook. Further movement of the clutch toward the center of the tube frame will cause sliding of the 50 hook to the position shown in Fig. 2, after which the clutches may descend in the usual manner. The arm 28 has a solid portion 38 lying under the lug 36, but for the purpose of the present invention it is sufficient if the clutch and tube 55

frame have coating parts one of which can engage the other to prevent movement of the frame away from the clutch during the wiping-in operation. The tube frame illustrated in Fig. 2 may be 5 similar to that shown in patent to Payne No. 1,807,748.

Each clutch has a pivotal support 40 with an 10 arm 41 pivoted about an axis 42 carried by a supporting frame 43. The position of the latter is determined by a rod 44 connected to a lever 45 which is held down by spring 46 against cam 47. The clutches are moved about their pivotal supports by means of a rod 48 having pivotal connection with the clutch as shown at 49 in Fig. 2. The 15 rod 48 is attached to a bell crank lever 50 and receives motion from an operating rod 51 actuated in the usual manner.

The loom frame supports an arch 60 from the rear of which extends a stand 61 supporting a fixed stud 62. An actuating lever 63 is pivoted about this stud and is moved by a rod 64 connected to a lever 65. The position of the latter is limited by a stop screw 66 and the lower end of lever 65 preferably carries a roll 67 for engagement with a cam 68 secured to the plate 22.

The forward end of lever 63 carries a lifter pin 69 which extends under an arm 70 also pivoted to the stud 62. The forward end of arm 70 is adjustably connected by means of link 71 to a floating carrier 72, the rear end of the latter being pivotally connected as at 73 to the lower arm 74 of the lever 75 also pivoted about the stud 62. The carrier link supports the brace 76 which may be secured thereto as shown in Figs. 6 30 and 7 and is given a contour as set forth in Fig. 1 to clear certain parts of the loom not shown in the drawings. The lower end of the brace is provided with a pushing and lifting finger 77 adapted for engagement with a bracket 78 secured to the back of the tube frame at a point 35 intermediate the ends of the latter.

A rod 80 passes through the rear end of arm 75 and through a lug 81 on the lever 63, projecting below said lug and through a compression 40 spring 82 and lock and check nuts 83.

In operation, the pull-over shaft presents the tube frames one at a time to the position shown in dotted lines in Fig. 1 and the arms 41 will move the clutches inwardly, so that the lugs 35 45 will unlatch the tube frame from the chain. The tube frame is then lowered and in order to facilitate the entry of the yarn tubes 31 between the binder warps B the frame is tilted so that the tubes assume a nearly horizontal position. This 50 is accomplished by a swinging of the clutch around the pivot 40 by means of link 48. After the tuft yarns Y and the tubes have been projected through and below the binders to take the position shown in Fig. 8 in dot and dash lines, the tube frame will be rocked toward a vertical 55 position with the spool over the frame, passing through the dotted and also the dashed lined positions shown in Fig. 8. At this time guide plates 90 already referred to, which lie between the 60 fingers 91 of a nose board 92, are in a rear position between the yarn tubes and exert a frictional resistance on the yarn tubes tending to bow the tube frame rearwardly.

The cam 68 is timed so that the lever 63 is 70 rocked in a counterclockwise direction as viewed in Fig. 1 while the tube frame is being moved angularly, or during the so-called wiping-in operation. This causes a forward yielding movement of arm 74 by a force transmitted through 75 arm 75 and the spring 82, the effect of which is

to move the carrier link 72 forwardly, or to the right, as viewed in Fig. 1. The cam 68 is shaped to cause the finger 77 to follow the tube frame as the same moves forwardly and upwardly during the wiping-in operation. It is this forward movement of the finger 77 with the moving tube frame which forms an important part of my present invention, since it is effective to brace the tube frame against rearward bending due to the friction of the plates 90.

It will be seen from an inspection of Fig. 3 that the horizontal force exerted by the finger 77 against the bracket 78 when the tube frame is inclined would have a tendency to unseat the ends of the tube frames from the clutches. The lug 36, however, overhangs the part 38 of the tube frame ear and the ends of the tube frame are therefore prevented from rising. It should be noted that the combined resistance of the spring 46 together with the weight of the parts between the projection 36 and the center 95 around which the clutch operating parts move is sufficient to hold the clutch down against the action of the lifter finger 77, the latter being effective only to prevent bending of the tube frame.

As the tube frame continues to roll near the end of the wiping-in operation, it assumes the position shown in Fig. 5, after which the arms 41 are raised to pull off yarn for the next row of tufts, and at this time the lug 69 engages the under side of the arm 70 to raise the link 71 and thereby elevate the lifter finger 77 and prevent sagging of the tube frame for a purpose accomplished heretofore as in patent to Robertson No. 1,603,411. After the tube frame has been temporarily brought to rest during its upward movement the knives not shown cut the tufts formed by the tube frame yarns, after which the tube frame is returned to the chain by the raising of arms 41 through the action of lever 45 and cam 47. The cam 68 is conveniently made with a separate part 110 adjustable radially and angularly with respect to the main part of the cam 68 to afford means to start motion of the finger 77 early or late, according to the timing of the tube frame operating devices.

I find in practice that it is desirable to provide a more accurate and delicate adjustment for the movements of the brace finger during the wiping-in operation than can conveniently be obtained from the relatively large cam 68. As shown more particularly in Figs. 6 and 7, a small stand 100 is secured to the arch by a bolt 101 passing through a vertical slot 102. The lower end of the stand has a horizontal slot 103 in which is adjustably mounted a support 105. The latter is adjustably positioned for engagement with the under side of the carrier link 72, which is provided with a relatively high face 106 and a lower face 107, between which is a small cam surface 108. Before the finger 77 begins to follow the tube frame forwardly in the wiping-in operation, the roll 105 will ordinarily be near face 106, as shown in Fig. 2 and during the forward movement of carrier link 72 already described the small cam 108 will ride over the support 105 and effect a slight lifting of the finger 77, as indicated in Fig. 6. The vertical position of the stud 104 as well as the horizontal location of the support 105 can be varied to give the requisite nicety of adjustment to cause the finger 77 to remain in bracing contact with the tube frame or the bracket 78 during the wiping-in operation.

From the foregoing it will be seen that I have provided means for preventing the forward thrust

of the bracing finger 11 from unseating the tube frame from the clutches, this result being accomplished to set forth specifically herein by the engagement of a part carried by the clutch with a part carried by or moving with the tube frame. Although I have shown the projection 36 for accomplishing this result because it is convenient to employ this part also for the purpose of unlatching the hook 32, yet I do not wish to be limited to this particular way of preventing the tube frame from becoming unseated in its clutch. It will also be seen that the small support 105 cooperating with the cam 108 effects a slight upward movement on the part of the bracing finger desirable to enable it to follow and remain in contact with the tube frame as the same is raised during the wiping-in operation.

Having thus described my invention it will be seen that changes and modifications may be made therein by those skilled in the art without departing from the spirit and scope of the invention and I do not wish to be limited to the details herein disclosed, but what I claim is:

1. In an Axminster loom, a series of guide plates substantially parallel to the binder threads, said series extending across the loom, a tube frame having tuft yarns and tubes to be projected between the binders and guide plates, clutch mechanism to support the tube frame, means to produce angular movements in the clutch to give the tube frame a wiping-in operation during which the clutch assumes an inclined position, a brace to engage and prevent rearward bending of the tube frame during the wiping-in operation, said brace acting in a direction tending to move the tube frame out of the clutch, and interconnecting means between the clutch and the tube frame to prevent the latter from being moved by the brace out of operative relation with respect to the clutch.

2. In an Axminster loom, a tube frame, means to give the tube frame a wiping-in operation during which the tube frame passes from an inclined to a substantially erect position, a pair of levers movable about a common axis, a link for each lever, means to pivotally connect the links independently of the levers, a brace carried by one of the links to engage and prevent rearward bending of the tube frame while the lay is in an inclined position relatively to a horizontal plane, a fixed guide and a cam fixed on one of the links to cooperate with the guide, movement of one of the levers moving the cam over the guide to elevate both links and the brace and at the same time move the brace forwardly, the lever capable of additional movement to elevate the tube frame independently of cooperation between the cam and the fixed guide.

3. In an Axminster loom, a series of guide plates extending across the loom, a tube frame with yarn tubes, a chain engaging ear on the tube frame, a clutch to engage the ear and give the same a disengaging movement preparatory to motion toward the cloth, means to give the clutch angular movements to give the tube frame its wiping-in operation and cause the yarn tubes to pass between the plates, the clutch and tube frame passing through an inclined position during the wiping-in operation, and the plates tending to bend the tube frame rearwardly, a brace to engage and prevent rearward bending of the tube frame during the wiping-in operation and exerting a force on the tube frame tending to move the ear away from the clutch when the latter is inclined, and interconnecting means between the clutch and the ear effective to resist said tendency of the ear to move away from the clutch and maintain the ear in operative relation with respect to the clutch.

EDWARD J. DACEY. 40
